CLIPBOARD ATTACHMENT FOR A VEHICLE STEERING WHEEL

Robert Beerli, Jr., 9456 La Luna,
Fountain Valley, Calif. 92708

Filed Jan. 6, 1972, Ser. No. 225,030

Term of patent 14 years

Int. Cl. D19—99

U.S. CL. D74—2

FIG. 1 is a rear perspective view of a clipboard attachment for a vehicle steering wheel showing my new design; FIG. 2 is a front elevational view thereof;

FIG. 3 is a top edge view of FIG. 2;

FIG. 4 is a right side edge view of FIG. 2, the left side being a mirror image thereof; and

FIG. 5 is a rear elevational view of FIG. 2.

I claim:

The ornamental design for a clipboard attachment for a vehicle steering wheel, substantially as shown and described.
